(57) **CLAIM**

The ornamental design for a battery portion of a vaporizer, as shown and described.

DESCRIPTION

FIG. 1 is a front perspective view of a battery portion of a vaporizer with a cartomizer inserted into the battery portion of a vaporizer, the cartomizer illustrated in broken lines; FIG. 2 is an exploded front perspective view of the battery portion of a vaporizer of FIG. 1 with the cartomizer removed from the battery portion of a vaporizer, the cartomizer illustrated in broken lines;

FIG. 3 is a top view of the battery portion of a vaporizer of FIG. 1;

FIG. 4 is a side view of the battery portion of a vaporizer of FIG. 1;

FIG. 5 is a front view of the battery portion of a vaporizer of FIG. 1;

FIG. 6 is a rear view of the battery portion of a vaporizer of FIG. 1; and,

FIG. 7 is a bottom view of the battery portion of a vaporizer of FIG. 1.

The broken lines in FIGS. 1, 2, and 3 depict environmental subject matter that forms no part of the claimed design.
